(57) **CLAIM**

The ornamental design for a dental syringe, as shown and described.

DESCRIPTION

FIG. 1 is a perspective view showing the new design for a dental syringe.

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a back view thereof.

The broken lines form no part of the claimed design, and any shading is provided to illustrate contour only and is not an indication of texture, gradient, etc.
